UNITED STATES PATENT OFFICE.

GUS F. LENK, OF DALLAS, TEXAS.

BURNING CHAMBER FOR INCINERATORS.

Application filed August 1, 1924. Serial No. 729,652.

To all whom it may concern:

Be it known that I, GUS F. LENK, a citizen of the United States of America, residing at Dallas, in the county of Dallas and State of Texas, have invented certain new and useful Improvements in Burning Chambers for Incinerators, of which the following is a specification.

This invention relates to new and useful improvements in burning chambers for incinerators.

The object of the invention is to provide means in a burning chamber for suspending large and slow burning matter in the chamber above the fire grates, whereby said matter is dried out and burned by fires both above and below it and cremated in a highly efficient and improved manner.

A further object is to provide such suspension means between baffle walls, whereby a greater circulation and more intense incineration may be carried out.

Another object is to provide such suspension means in combination with pre-drying and liquid collecting means in the chamber, so that matter delivered to the suspension grates will be more or less free from liquids and the latter prevented to a large extent, from passing to the fire grates and ash pits.

A still further object is to provide suspension grates composed of water conductors, whereby said grates are prevented from burning out and whereby hot water and steam may be obtained for various purposes.

Another object is to provide a burning chamber having a baffle wall therein with a flame passage therethrough and suspension grates on each side of said wall, whereby the flames pass through said passage above and below the grates.

A further object is to provide doors whereby access through the front wall of the chamber may be had to the upper surface of the suspension grates as well as to the fire grates below, so that both may be efficiently stoked and non-combustible matter easily removed from either.

A construction designed to carry out the invention will be hereinafter described together with other features of the invention.

The invention will be more readily understood from a reading of the following specification and by reference to the accompany-

ing drawings, in which an example of the invention is shown, and wherein:

Fig. 1 is a front elevation of an incinerator constructed in accordance with my invention,

Fig. 2 is a horizontal cross-sectional view above the floor line,

Fig. 3 is a horizontal cross-sectional view on the line 3—3 of Fig. 5,

Fig. 4 is a longitudinal vertical sectional view on the line 4—4 of Fig. 5,

Fig. 5 is an enlarged transverse vertical sectional view on the line 5—5 of Fig. 1,

Fig. 6 is a cross-sectional view taken on the line 6—6 of Fig. 5, and

Fig. 7 is a detail of one of the roof blocks.

In the drawings the numeral 10 designates a base upon which a front wall 11, an end wall 12, a rear wall 13 and an end 14 are erected. These walls and the base are suitably constructed in accordance with incinerator engineering. The rectangular structure formed by these parts is comparatively shallow from front to rear in proportion to its length between the end walls. This is an important feature as it permits all parts of the interior to be reached through openings in the front wall, with a short handle rake and thus cuts down the stoking room usually required in front of the incinerator.

A floor 15 is supported at the upper ends of the wall and is composed of a concrete mixture reinforced by I-beams 16 extending at right angles to each other and having their ends supported in the walls. The incinerator is charged from the floor. A vertical division wall 17 adjacent the wall 14 divides the interior of the incinerator, the greater portion, about four-fifths more or less, lying to the right (Figs. 3 and 4) and constituting a main or burning chamber. I provide a floating or detached roof or arch for this chamber composed of fire resisting blocks or tile 18, suspended from clamps 19 (Fig. 7) supported by eye bolts 20 depending from hangers 21 clamped to the beams 16. These blocks may assume a desired form and while fitting together are not tied to the walls of the furnace, thus allowing for expansion and contraction and permitting ready removal and replacing.

Over the rear portion of the chamber the roof is horizontal, but is inclined down-

wardly over the front portion thereof. By using square blocks uniformity is had, and rectangular charging hoppers 22 may be used. The hoppers have their upper ends 5 flanged and countersunk in the floor 15. Each hopper has a vertical collar 23 secured to its lower end and surrounded by the blocks 18 of the roof. The details of the hopper form the subject matter of a co-pending application filed August 1, 1924, 10 Ser. No. 729,650. In each collar is hinged a cover composed of a fire resisting tile 24 secured in a back 25. The tile rests upon an interior flange 26 at the bottom of the collar. From the front end of each cover a flexible connection 26' extends upward and passes behind a pulley 27 on the rear wall 13 of the building. By this means the cover 15 may be swung upward in a convenient 20 manner.

The hoppers have their greatest length directed forwardly as is shown in Fig. 2 and are located near the rear wall 13. Within the burning chamber and under the hoppers 25 is an evaporating and drying table 28 inclined downwardly from the rear wall and having its front end supported above the base 10 on a vertical wall 29. The table is suitably formed of fire resisting material 30 and may be made in sections or block so as to be replaced. This elevated table has a longitudinal sump or trough 30 along its front edge for catching and retaining the liquids, whereby the latter are evaporated 35 and prevented from flowing down into the ash pits. This table is arched over a flue or tunnel 32 extending parallel to the rear wall 13 and behind the wall 29. The bottom of the tunnel is formed by the base 10. 40 As will be hereinafter explained the hot gases and air currents escaping from the burning chamber pass through said tunnel, thus heating the table from the underside.

The table 28 and tunnel 32 constitute drying or pre-heating means and are specifically covered in my co-pending application filed August 1, 1924, Ser. No. 729,653. As will be obvious from the following description, it will be seen that any type of table 45 or equivalent means heated in any suitable manner could be used.

The burning chamber is divided by transverse vertical baffle walls 33 extending from the base 10 to the roof and from the front 50 wall 11 to the wall 29 and the front edge of the table. Between the walls 33 and on each side thereof, are fire grates 34 of any suitable type. These grates are supported by the walls 11, 12, 17, 29 and 33 above the 55 base 10 and about midway the height of the front of the table 28. Ash pits 35 are formed below the fire grates and access is had thereto through doors 36 in the front wall 11.

60 Above the grates 34 are suspension grates

37 located in a plane substantially flush to the front edge of the table, but subject to variation. I have shown three units (Fig. 3) separated by the baffle walls 33. Each unit is composed of a front header 38 and a rear header 39 parallel to the front wall 11 and the table 28, respectively the heads are connected by spaced tubes 40 forming the grate bars. A water supply pipe 41 extends into the wall 12 and is connected to 70 the adjacent rear header 39. The front header of the first grate is connected to the front header 38 of the second grate by a coupling 42, while the rear header 39 of the second grate is connected to the rear header 80 of the third grate by a coupling 43. A discharge pipe 44 leads from the end of the header 38 of the third grate adjacent the wall 17. It will be apparent that water entering the first grate (Fig. 3) at the right 85 will flow through the various units and escape through the pipe 44 either as hot water or steam.

The pipe 44 is connected with a vertical pipe 45 which enters a manifold 46 disposed along the base 10. The right hand end (Figs. 3 and 6) of the manifold is closed by a cap 47, while a valve 48 is connected to the other end and has a nipple 49. Risers 50 extend from the manifold and are connected to nozzles 51 extending through the front wall 11 into the ash pits 35 below the grates 34. Steam may thus be supplied in jets from the nozzles. Hot water may be drawn off by opening the valve. Doors 52 in the front walls give access to the spaces between the grates; while other doors 53 give access to the grates 37. Flared liners 54 in the wall 11 at each of these doors make for free stoking and access to any part of 105 the burning chamber.

Each baffle wall has a central opening 55 extending from a point between the grates 34 and 37 to the roof of the burning chamber. A similar but larger opening 56 is 110 provided in the wall 17 for the escape of the products. It will be seen that the air currents and flames will pass through the openings 55 in the baffle walls above the grates 34 and above and below the grates 115 37, thus thoroughly igniting and burning matter deposited upon said grates. The flames and currents will also whip around the rear ends of the baffle walls and pass over the front of the table 28. These flames, currents and gases will be drawn toward the opening 56 and at this point the fire will be most intense, providing a cut-off fire 120 through which all products must pass.

The essential feature of the invention being the suspension grates and the baffle walls, it will be seen that the garbage and trash might be delivered directly to said grates. The openings in the walls permit a free passage and circulation of the flames 125 130

and allow them to pass above and below the matter suspended on said grates. The shallow burning chamber and the flared openings permit the grates to be efficiently stoked and also afford a ready means of removing tin cans and other non-combustible matter.

So far as this invention is concerned the outlet 56 may connect with a passage for conducting the products to a smoke stack. 10 In the drawings I have shown a super-heating chamber 57 and a combustion chamber 58 formed between the division wall 17 and the end wall 14. The chamber 57 is connected with the opening 56, while the 15 chamber 58 is connected with the tunnel 32. A grille 59 is placed at the entrance to the tunnel.

The products passing through the tunnel heat the table 28. Ducts 60 lead from the 20 discharge end of the tunnel and are connected with a smoke stack 61. The stack creates a draft so that the products are drawn through the openings 55 in the baffle walls and the opening 56, whereby combustion is promoted in the burning chamber.

Various changes in the size and shape of the different parts, as well as modifications and alterations may be made within the scope of the appended claims.

30 What I claim, is:

1. In an incinerator, the combination of a burning chamber having a charging hole in its roof and an outlet at one side, a baffle wall in the chamber having an opening therethrough, fire grates extending on each side of the wall, the opening of the wall extending above said fire grates, and suspension grates on each side of the wall, the opening of the wall extending above and below the suspension grates.

2. In an incinerator, the combination of a burning chamber having a charging hole in its roof, an inclined drying table in the chamber under the charging hole, a baffle wall at right angles to the table, suspension grates on each side of the baffle wall con-

tiguous to the table, and fire grates on each side of the baffle wall spaced below the suspension grates in front of the table.

3. In an incinerator, the combination of 50 a burning chamber having a charging hole in its roof, an inclined drying table in the chamber under the charging hole, a baffle wall at right angles to the table, suspension grates on each side of the baffle wall contiguous to the table, and fire grates on each side of the baffle wall spaced below the suspension grates in front of the table, the baffle wall having an opening extending 55 above and below the suspension grates. 60

4. In an incinerator, the combination of 65 a burning chamber, an inclined drying table at the rear of the chamber, baffle walls extending from the front wall of the chamber to the table, suspension grates between 70 and on each side of said baffle walls contiguous to the table, fire grates under the suspension grates, the baffle walls having vertical openings extending above and below the suspension grates, and doors in the front wall giving access to the surfaces of 75 the suspension and fire grates.

5. In an incinerator, the combination of 80 a burning chamber, a drying table extending along the rear wall of the chamber, the chamber having a charging hole over the table, vertical baffle walls spaced from the sides of the chamber and also spaced from each other and extending from the table to 85 front wall of the chamber, the baffle walls having communicating openings therein, fire grates in the chamber separated by the baffle walls and below the front edge of the table, and suspension grates over the fire grates and contiguous to the table and the openings in the baffle walls, the space above the table being unobstructed whereby the hot gases may pass around the rear ends of the baffle walls and over the table.

In testimony whereof I affix my signature.

GUS F. LENK.
